1 Claim. (Cl. 212—70)

This invention relates to mobile hoisting cranes mounted on a vehicle.

More particularly, this invention relates to a mobile crane which is mounted on a vehicle and which comprises a preferably telescopically extendable mast or pole which is in a lowered position is placed horizontally on the vehicle.

One main object of the invention is to provide a crane of said type which while possessing extremely high hoisting capacity can be given a substantially longer mast than has been possible with cranes of this type hitherto known.

Another object of the invention is to provide a crane of the type under consideration the mast of which in spite of its length is adapted in a vertical position to be anchored rigidly in the vehicle.

Still another object of the invention is to provide a crane of the type under consideration the mast of which in its vertical position can be swung out from the vehicle. The crane may then be used either with an arm or jib attached to the mast and projecting therefrom at an angle or be brought to take an inclined position to the vertical so that it may serve without jib as a crane for lifting particularly heavy loads.

A still further object of the invention is to provide a crane of the type under consideration the mast of which in lowered state on the vehicle takes a position with both ends projecting over the ends of the vehicle so that the chassis thereof does not cause any additional prolongation of the total length of the vehicle and the crane during transportation.

Further objects and advantages of the invention will become apparent from the following description considered in connection with the accompanying drawings, which form part of this specification and of which:

FIG. 1 is a side view of the vehicle with a crane mounted thereon and the mast thereof in lowered position.

FIG. 2 shows a portion of FIG. 1 in the same view but in a larger scale.

FIG. 3 is a side view of the crane in elevated position with a jib applied to the mast.

FIG. 4 shows a portion of the vehicle and the crane in the position of FIG. 4 in a larger scale.

FIG. 5 shows the same portion of the vehicle and the mast but with the latter swung out so as to form an angle towards the vertical.

Referring to the drawings, the vehicle is generally denoted by 10. It may generally have the form of a lorry with double pairs of rear wheels 12 and one pair of front wheels 14. On the chassis of the vehicle there are arranged flaps 16, 18 suitably pivotable about a vertical axis and provided with support members 20, 22 adjustable in the vertical direction and intended to be brought into contact with the ground and thereby to increase the stability of the chassis when the hoisting crane mounted on the vehicle is in an elevated position. In the embodiment illustrated a platform or stage 24 is disposed pivotably about a vertical axis located approximately between the rear wheels 12.

The hoisting crane comprises a mast which may be composed of at least two parts 26, 28 displaceable relatively one another in a telescopic manner. The lower mast

part 26 is at a distance from its lower end provided with two pivot pins 30 received in bearings 32 which in the illustrated embodiment are anchored to the pivotable platform 24. The bearings 32 are provided with an opening 34 which may be opened or closed by means of a latch device 36 pivotable by 180°. When the mast is in the lowered position shown in FIG. 2 or in the working position according to FIGS. 3 and 4, the pins 30 are enclosed within the stationary bearings.

10 In the lowered position which the crane occupies during transportation or like conditions the mast 26, 28 extends from the rear part of the lorry forwards past the driver's cab 39 and a support 40 on the front part of the lorry from which it projects for a distance ahead of the hood. 15 Due to the feature that the pins 30 and the bearings 32 are located in a spaced relation to the end of the mast and the rear end of the vehicle, said mast end also will project rearwardly from the chassis of the vehicle. The length of the vehicle with lowered mast is thus determined only 20 by longitudinal dimension of the latter. An arm or jib 38 is articulated onto the upper end of the upper part 28 of the mast and in the lowered position extends rearwardly in a position superimposed to the two mast parts. A second arm 40 is secured to the mast part 28. 25 Disposed at the lower end of the lower mast part 26 are pulleys 42. Pulleys 44 and winch 46 are mounted on the platform 24. A cable 48 is guided over pulleys 42, 44 and winch 46 so as to give a high mechanical advantage. This winch 46 is driven by an electric motor 49 which gets 30 current from an electric generator (not shown) driven by the internal combustion engine of the lorry. By means of the winch 46 the mast 26, 28 can be elevated from the position shown in FIG. 1 to the position of FIG. 3 by pivotal movement about the pins 30.

35 The pins 30 are disposed behind the turning axis of the platform 24 for which reason the mast in its elevated position exerts a moment on the bearings of the platform corresponding to the product of the spacing from the said turning axis and the weight of the mast and the load. On 40 the platform there are arranged powerful counterweights 50 which by means of a windlass, not shown, may be displaced from an inactive rear position shown in FIGS. 1 and 2 to a fore position shown in FIGS. 3 and 5 where they are located on the opposite side of the platform and thereby produce a moment counteracting the moment exerted by the mast. The moment arm of the counterweights in the last-mentioned position may be greater than the moment arm of the mast.

The mast part 26 is at its lower end provided with two 50 pins 51 which when the mast during elevation comes near the vertical position fit into bearings 52 on the vehicle or the platform 24 which bearings 52 are provided with slots 54 to permit the passage of the pins. The bearings 52 consist of bushings adapted for cooperation with a latch 55 member 60 which upon introduction of the pins 51 into the bearings are turned by 180°, the pins 51 then being locked on all sides in the same manner as the pins 30. Thereby the position of the mast is fixed on all sides relatively to the vehicle. The pins 30 are suitably located 60 on the rear edge of the mast part 26 and the pins 51 approximately at the middle plane of the mast.

The mast part 28 is then hoisted up out of the mast part 26 in a manner known per se. The jib 38 is lifted from a vertically depending position upwards by means of 65 cables 62 passing over the free end of the minor arm 40 and extending to the free end of the jib 38. The cables 62 cooperate with cable 64 operated from the vehicle by means of a windlass (not shown) driven by the engine so that the jib 38 may be given any desired angular position relative to the horizontal plane. A load hook 66 is attached to a cable 68 operated from the vehicle by means of an engine-driven windlass (not shown) for

lifting and lowering of said load hook. The arm 40 is fixed to the jib 38 for movement therewith and consequently with the jib disposed parallel to the mast, as shown in FIG. 1, the arm 40 will project outwardly of the mast and jib on the same side as the jib. As a result a pull on the cable 62 would not result in movement of the arm 40 and jib 38 to the position shown in FIG. 3. In order to permit this operation, there is provided a cable guide bracket 70 which projects from the arm 40 on the side opposite the jib 38 and in the lowered position of the jib 38 the cable 62 engages the bracket 70 in order to provide a lever arm for causing initial movement of the jib 38 from lowered position upon exerting a pull on cable 62.

According to the invention, the hoisting crane may also be used without the jib 38 when particularly heavy objects are to be hoisted. In such a case the jib 38 together with the arm 40 is removed from the mast 28 when this latter rests in a lowered position on the lorry according to FIG. 1. The cables 62 are secured to the mast part 28, for example about a pin 62 (FIG. 1). Thereupon the mast is raised in the same manner as described above. After the pins 51 have been anchored in the bearings 52 the latch member 36 is turned by 180° so as to release the upper pins 30. The mast can now be pivoted about the lower pins 51 with the pins 30 moving away from the bearings 32 and the mast taking the inclined position shown in FIG. 5 which positions the upper part outwardly of the vehicle. Thereby a space is obtained for the lifting of objects by means of the cable of the load hook 66 running over the upper end of the mast instead of the jib 38.

The mast may be pivoted rearwardly down to approximately horizontal position over the ground. The cable system 64 is then preferably brought to cooperate at the base with a support device 72 which is tiltable about a horizontal axis provided on the vehicle or its platform 24 and which when the mast is turned rearwards forms an upstanding level arm enabling the cables 62, 64 to act on a sufficiently great moment arm for raising the mast from the horizontal position over the ground to any desired elevated angular position up to the vertical.

While one more or less specific embodiment of the in-

vention has been shown and described, it is to be understood that this is for purpose of illustration only, and that the invention is not to be limited thereby, but its scope is to be determined by the appended claim.

What I claim is:

A mobile crane comprising a vehicle, a mast, a pair of combined locking and pivot pins fixed to said mast adjacent one end, a second pair of combined locking and pivot pins fixed to said mast at a location longitudinally spaced from said first pins, a mast supporting structure on said vehicle, a pair of bearings on said structure for pivotally receiving said first pins, said bearings having transverse slots to permit movement of said first pins into and out of said bearings, latch means for releasably retaining said first pins in said bearings, a second pair of bearings on said structure disposed to pivotally receive said second pins, said second bearings having transverse slots to permit movement of said second pins into and out of said second bearings, second latch means for releasably retaining said second pins in said second bearings, cable means for pivotally moving said mast about the axis of said second bearings from a horizontal inoperative position to a vertical operative position wherein said first pins are received and latched in said first bearings, and second cable means for pivotally moving said mast about the axis of said first bearings to inclined operative positions with said second pins released from said second bearings, whereby said mast may be positively latched at longitudinally spaced points in vertical operative position and upon release of said second latch means is pivotally movable to inclined operative positions.
